SILVER WASHING BASKET

Sol Kesilman, 7930 Oak Hill Drive, Cheltenham, Pa. 19012; Hyman B. Penn, 435 Twickenham Road, Glen-side, Pa. 19038; and Milton Kravitz, 7908 Rolling Green Road, Cheltenham, Pa. 19012

Filed Mar. 7, 1966, Ser. No. 1,319

Term of patent 14 years

(Cl. D44—29)

FIG. 2

FIG. 3

FIG. 4

FIG. 5

FIG. 1 is a perspective view of a silver washing basket showing our new design.

FIG. 2 is a top plan view thereof.

FIG. 3 is a side elevational view thereof, showing the side that is not visible in FIG. 1.

FIG. 4 is a bottom plan view thereof.

FIG. 5 is an end elevational view thereof, showing the side that is not visible in FIG. 1.

We claim:

The ornamental design for a silver washing basket, substantially as shown and described.
